CLAIM

The ornamental design for a combined fastening bolt and locking washer therefor, substantially as shown and described.

DESCRIPTION

FIG. 1 is a perspective view of a combined fastening bolt and locking washer therefor showing my new design;

FIG. 2 is a side elevational view of the bolt, shown separately for clarity of illustration, both sides being identical;

FIG. 3 is a top plan view of FIG. 2;

FIG. 4 is a side elevational view of the washer, also shown separately for ease of illustration;

FIG. 5 is a top plan view of FIG. 4;

FIG. 6 is an end elevational view of FIG. 4, both ends being identical.

FIG.1

FIG. 4

FIG. 5

FIG. 6

FIG. 2
